DESIGN FOR A SHOE SOLE

Gavan S. C. Ivan, Bridgeton, N. J.

Application August 23, 1940, Serial No. 94,574

Term of patent 14 years

To all whom it may concern:

Be it known that I, Gavan S. C. Ivan, a citizen of Austria, residing at Bridgeton, in the county of Cumberland and State of New Jersey, have invented a new, original, and ornamental Design for Shoe Soles, of which the following is a specification, reference being had to the accompanying drawing, forming part thereof.

The figure is a perspective view of a shoe sole showing my new design.

My design for a shoe sole is characterized by the radiating specific arrangement of the three oval plugs, having their oval ends pointing toward the outer edges of said shoe sole in a manner as shown.

I claim:

The ornamental design for a shoe sole, as shown and described.

GAVAN S. C. IVAN.
